UNITED STATES PATENT OFFICE.

GILBERT J. HARRIS, OF ATHOL, MASSACHUSETTS.

CHISEL.

No. 841,517.

Specification of Letters Patent.

Patented Jan. 15, 1907.

Application filed August 11, 1906. Serial No. 330,200.

To all whom it may concern:

Be it known that I, GILBERT J. HARRIS, a citizen of the United States of America, residing at Athol, in the county of Worcester 5 and State of Massachusetts, have invented new and useful Improvements in Chisels, of which the following is a specification.

This invention relates to improvements in carpenters' chisels or similar tools having a driving end or head for the reception of blows from a hammer or other driving-tool, the object of the invention being to provide a simple, strong, durable, and secure construction of driving end or head, whereby the handle 10 of the chisel or tool may be used for a long period without liability of the blows of the driving-tool splitting, mashing, or otherwise injuring the driving end of the handle.

In the accompanying drawings, Figure 1 is 20 a side elevation of a chisel embodying my invention. Fig. 2 is a vertical cross-section thereof. Fig. 3 is a sectional plan view on line 3-3 of Fig. 2.

Referring to the drawings, 1 designates the 25 tool or chisel, provided at its upper end with a socket 2 to receive the tang 3 of the driving head or handle 4. The said head or handle 4 is annularly reduced at its upper end, as shown at 5, thus providing at the base of such 30 reduced portion an annular shoulder 6, the lower end of the reduced portion being outwardly flared or tapered, as indicated at 7.

The head or handle is provided with a pair 35 of saw cuts or grooves 8 and 9, arranged at right angles to each other and crossing or intersecting in the center line of the handle, the grooves preferably being of greater depth than the reduced portion 5 to extend a suitable distance below the same.

40 Surrounding the reduced portion 5 is a reinforcing band, ring, or ferrule 10, whose internal surface is flared, as indicated at 11, to correspond to the contour of the flared surface 7 of the reduced portion 5. A wedge or spreader 12 is adapted to fit within the 45 grooves 8 and 9 and comprises a casting of cross or X form in horizontal section, providing a series of flanges or wings 13 to fit within the respective portions of the grooves 8 and

50 9. The wings are beveled or tapered, as shown at 14, to form wedges, whereby the walls of the portion 5 of the head or handle are forced or crowded outwardly into frictional engagement with the ring or ferrule 5,

thus firmly and securely holding the parts in 55 interlocking engagement.

After the ferrule has been applied to the reduced portion 5 the spreader or extender 12 is inserted from above into the grooves 8 and 9 and then driven down into the same until 60 its upper surface lies flush with the upper surfaces of the portion 5 and ring, the intermediate portions of the outer edges of the flanges of the spreader resting in engagement with the intermediate surfaces of the inner face of 65 the ring, thus securing a more effective engagement. It will thus be seen that the spreader, in addition to locking the ring in position by an action which insures its own firm retention, coöperates with the ring to form a 70 metallic head of great strength to resist the blows of the driving-tool on the handle, thus enabling the latter to be used for a long period without splitting or becoming mashed under the impact of the blows. The construction is simple, may be embodied in tools of this character at a comparatively low cost, and, as will be readily understood, is exceedingly effective in prolonging the life of such 75 tools to a material extent. 80

Having thus described the invention, what is claimed as new is—

A tool-handle provided with a reduced end having its lower surface externally beveled and formed with transverse slots arranged at 85 right angles to each other, said slots opening through the upper edge of said reduced end and terminating below the base of said beveled portion, a ring or ferrule encircling said reduced portion and having its lower portion 90 internally beveled to bear against the beveled surface thereof, and a spreader of cruciform shape driven into said slots, said spreader being coextensive in depth with the slots and terminating at its outer end flush with the 95 outer end of the ferrule and providing a series of wings tapered to wedge form to spread the walls of the reduced end into binding engagement with the ferrule, the latter being arranged to bear against said wings above 100 the beveled surfaces.

In testimony whereof I affix my signature in presence of two witnesses.

GILBERT J. HARRIS.
